UNITED STATES PATENT OFFICE

127,648

DESIGN FOR A COMBINED BROOCH AND LOCKET

Gene Verrecchio, Providence, R. I., assignor to Cohn & Rosenberger Inc., New York, N. Y., a corporation of New York

Application April 16, 1941, Serial No. 100,397

Term of patent 3½ years

To all whom it may concern:

Be it known that I, Gene Verrecchio, a citizen of the United States of America, residing in Providence, county of Providence and State of Rhode Island, have invented a new, original, and ornamental Design for a Combined Brooch and Locket, of which the following is a specification, reference being had to the accompanying drawing, forming part thereof.

Fig. 1 is a plan view of a combined brooch and locket showing my new design.

Fig. 2 is an edge view thereof.

Fig. 3 is a plan view showing the locket portion in partly opened position.

I claim:

The ornamental design for a combined brooch and locket, substantially as shown.
